UNITED STATES PATENT OFFICE.

SILAS R. DIVINE, OF LOCH SHELDRAKE, NEW YORK.

DESIGN FOR A FERRULE FOR FLAIL-STICKS.

SPECIFICATION forming part of Design No. 32,444, dated April 3, 1900.

Application filed January 22, 1900. Serial No. 2,403. Term of patent 14 years.

To all whom it may concern:

Be it known that I, SILAS R. DIVINE, a citizen of the United States, and a resident of Loch Sheldrake, in the county of Sullivan and State of New York, have invented a certain new and useful Design for a Ferrule for Flail-Sticks, of which the following is a specification, reference being had to the accompanying drawings, forming part hereof.

10 Figure 1 is a representation in perspective of a ferrule for flail-sticks embodying my new design viewed from its lower end, and Fig. 2 is a similar representation of the same viewed at its upper end.

15 The ferrule comprises a hollow cylinder A, which is open at its lower end a and has a head portion b, which closes its upper end, and in which head portion is a central annular aperture b', together with a ring C, which 20 has a cylindrical projection c extending radially from the periphery of the ring into the aperture b' in the head b of the cylinder A.

The essential feature of the described design for a ferrule for flail-sticks is a hollow cylindrical body, which is open at its lower 25 end and has a head portion which closes its upper end, with a central annular aperture in said head portion, together with a ring which has a cylindrical projection extending radially from its periphery into said aperture in 30 said head portion.

What I claim as my invention, and desire to secure by Letters Patent, is—

The design for a ferrule for flail-sticks herein shown and described.

Signed at New York city, in the county of New York and State of New York, this 30th day of December, A. D. 1899.

SILAS R. DIVINE.
